ROTARY SEAL FOR FURNACE TOPS

Waring Lennox Dawbarn, Winchester, Mass., assignor to Arthur D. Little, Inc., Cambridge, Mass., a corporation of Massachusetts

Application October 19, 1949, Serial No. 122,185

7 Claims. (Cl. 214—36)

1

This invention relates to sealing means for preventing the flow of gases between parts which are moving with respect to each other. More particularly it relates to sealing means for revolving distributors located at the tops of blast furnaces.

Blast furnaces are customarily provided with an upper hopper which rotates and which projects, at its lower end, downwardly into the chamber between the upper and lower bells. Since the chamber walls do not rotate, an annular space must be provided between the outside wall of the hopper and the upper end of the chamber walls through which the hopper projects, to permit rotation of the hopper. During operation of the furnace, there is, during at least a part of the charging cycle, a pressure differential between the chamber and the outside atmosphere, so that furnace gases, generally dust-laden, pour out through the annular space between the hopper and the chamber walls, in the absence of sealing means in said space. Aside from the undesirability of discharging gases and dust to the atmosphere, there is the serious hazard to personnel working at the top of the furnace. This hazard, especially from the furnace gases, largely due to CO content, has led to the safety requirement that no personnel shall go singly to the furnace top; yet even when two or three men are present there together, serious poisoning effects from the gas are not infrequent. Furthermore, the dust associated with the escaping gases is strongly abrasive, and has a severe wearing effect as it escapes.

These drawbacks are serious enough when the furnace is operated under normal conditions; they are of course increased when the furnace is operated under high top pressure.

Although various sealing means have been used in efforts to overcome these difficulties, they have not proved satisfactory in actual practice, especially when operating under high top pressure. They are either impractical to install, or they are ineffective because of the nature of the gases being restrained, i. e. their pressure, temperature, composition, and abrasive-dust content, or because of the slight vertical and lateral irregularities in the movements of the small bell hopper. An increase in pressure within the bell chamber tends to raise the small bell hopper slightly, while the rotation of the small bell hopper, first in one direction and then in the other, causes a slight lateral shift in the position of the hopper. Seals hitherto used have been too rigidly fixed in their positions to accommodate these vertical and lateral irregularities without leakage of gas.

2

The present invention provides a relatively simple means for overcoming these drawbacks and for providing a gas-tight seal between relatively-moving parts, which seal is effective to prevent the passage of abrasive-laden gases, under pressure, between said relatively-moving parts. And while it is of particular value for use in blast furnace tops, as aforesaid, it is likewise of value in providing a gas-tight seal between two bodies so placed with respect to each other that there is an annular space between them, said bodies being rotatable with respect to each other about an axis which is the axis of said annular space, the seal being for the purpose of preventing passage of gas through said space.

For convenience and brevity, however, this seal will now be described in detail with reference to its use in a blast furnace top, in connection with the accompanying drawings, wherein:

20 Fig. 1 is a schematic view of the top portion of a typical blast furnace employing the sealing means of this invention;

25 Fig. 2 is a vertical sectional elevation through the rotating hopper and seal of such a blast furnace;

30 Fig. 3 is an enlarged view, in cross section, of a portion of Fig. 1 showing in greater detail the features of the seal; and

35 Fig. 4 is a sectional plan view taken along the line 4—4 of Fig. 3.

In Fig. 1 there is shown a portion of the top of a typical blast furnace, in which the sealing means of the present invention is employed. This furnace top includes the conventional rotating small bell hopper 10, small bell 12, large bell hopper 14, large bell 16, bell chamber 18 between said small bell and said large bell and top wall 20 of said bell chamber 18. Small bell 12 is raised and lowered by bell rod 22, and large bell 16 is raised and lowered by bell rod 24. The top of the blast furnace shaft is indicated by numeral 26. Small bell hopper 10 is rotated intermittently by means shown generally by reference numeral 28, so that the charges dumped into said hopper will be distributed sufficiently evenly upon small bell 12. All of the foregoing parts and their operation are conventional in blast furnace practice and construction.

As shown in more detail in Fig. 2, hopper 10 projects downwardly into bell chamber 18 through an opening 32 in top wall 20 of said chamber. This opening is thus defined by the upper edge 34 of top wall 20 and the adjacent side of hopper 10, and is substantially annular in shape, with an axis common to that of edge 34 and hopper 10.

Hopper 10 is supported in conventional manner, e. g. by rollers 36 which support ring member 38 attached to flange 40 projecting from hopper 10; guide rollers 42 are also provided. These guide rollers 42 restrict upward movement of the hopper 10 caused e. g. by increase in pressure in bell chamber 18, although as already pointed out they do not entirely prevent such upward movement. Hopper 10 is rotated in conventional manner, e. g. by motor or other power means 28 which meshes with teeth 44 provided around the periphery of ring member 38. As the hopper is thus rotated, first in one direction and then in the opposite direction, there is a slight lateral movement of the hopper, as already stated. It is impractical, if not impossible, to construct a furnace top in such a manner as to avoid these vertical and lateral movements.

When the small bell 12 is in closed position and large bell 16 is open or not tightly seated, there will be superatmospheric pressure in bell chamber 18 in an amount depending upon the pressure within the top of blast furnace shaft 26. These gases, laden with more or less dust of abrasive nature will, unless prevented, pour out through opening 32, wearing away the edge 34 and the adjacent side of hopper 10 and contaminating the air, especially around the furnace top, with gases poisonous to personnel.

The seal of the present invention is mounted with relation to edge 34 and hopper 10 and effectively prevents the passage of air or other gases through space 32 in either direction, regardless of the slight vertical and lateral movements of hopper 10, and of variations in pressure in chamber 18 including sudden surges due to slips and rolls in the furnace. The seal comprises several parts, as shown generally in Fig. 2 and in more detail in Figs. 3 and 4. These parts will now be described.

Attached to the periphery of hopper 10, e. g. to adjacent flange 40, is a supporting ring 46, to which in turn is attached by bolts 47 flexible member 48 of cylindrical shape, said flexible member being spaced radially from said hopper. Ring 46 may conveniently be in say six sections, for convenience in attaching to existing furnaces, and its attachment to hopper 10 is in gas-tight relation. Flexible member 48 is also attached in gas-tight relation to ring 46; this relation is assured by providing metal ring 50 which surrounds flexible member 48 and is held tightly in position by bolts 47. Another cylindrical member 52, non-yielding and preferably of metal, is provided to fit around flexible member 48 so that the latter slides against it as hopper 10 is rotated. This member 52, which may also be made in say six sections for convenience in installing, is mounted in gas-tight relation with edge 34 of top 20, e. g. by bolts 54 extending through ring 56 to spider 58, which is attached to the top of edge 34 by bolts 59. Conventional packing 60 may remain in place, if desired, but it is not necessary.

Cylindrical member 52 is provided with an inner lip 62, which holds an annular buffer member 64 which is kept in position by annular retaining ring 66 fastened to lip 62 by bolts 68. Buffer member 64 is preferably of flexible material and may be in the form of a ring or a hollow tube. It bears against the lower end of flexible member 48, in sliding relation, and serves to maintain said member 48 in contact with member 52. By this means, flexible member 48 is prevented from pulling away from member 52

during the slight lateral movements of hopper 10 or on the occurrence of sudden sharp changes in pressure within chamber 18, including possible momentary occurrence of sub-atmospheric pressure therein, which might otherwise result in drawing air into said chamber through the seal. Such introduction of air creates a fire or explosion hazard in view of the combustible nature of the top furnace gases.

To promote ease of sliding between the two contacting cylindrical members 48 and 52, a lubricant is introduced through lines 70 and 72 from any convenient source (not shown). This lubricant, which may advantageously be of oil and colloidal graphite, works up and down from its distribution points over all of contacting surface 74 between cylindrical members 48 and 52, to facilitate the sliding of said members with respect to each other. Distributing wells or reservoirs 75 may be provided, if desired, in the inner face of member 52 at points where the oil lines emerge, to assist in providing a body of lubricant against the outer face of member 48 and assist in spreading the lubricant over the contacting surfaces.

Member 48 is made flexible in order to accommodate the already-mentioned slight vertical and lateral irregularities in the movement of hopper 10 as it revolves. Any good rubber or synthetic rubber composition having toughness and dimensional stability and a reasonable degree of heat stability is satisfactory for fabrication of member 48, as well as of buffer member 64.

It is clear from the foregoing that cylindrical members 48 and 52, and buffer member 64, as well as hopper 10, space 32, and edge 34, all have a common axis, which is located essentially at the center line of the bell rods. Such concentricity is of course necessary for the proper close sliding fit at surface 74 during rotation of hopper 10.

During operation of the blast furnace, the cylindrical member 52 of the seal of this invention remains in fixed position, being so held by the supporting means hereinabove described with respect to top edge 34 and in gas-tight relation therewith. Annular buffer member 64, being attached to member 52, likewise remains in fixed position. Flexible member 48, however, rotates as hopper 10 rotates, and during this rotation it is normally held in gas-tight relation against member 52 along surface 74 by gas pressure within chamber 18, which pressure bears against the inner cylindrical surface 76 of member 48. In the event that such gas pressure falls to ambient pressure, or below, annular buffer member 64 holds member 48 against member 52 in gas-tight relation.

While the seal of this invention has been described in detail in connection with its use in blast furnace tops, it may of course be used in many other locations where there are two contiguous bodies with an opening therebetween which it is desired to seal, and where one of said bodies rotates with respect to the other, the opening being substantially annular in shape. Various such uses within the scope of the appended claims will suggest themselves to those skilled in the art.

I claim:

1. In a blast furnace having an upper bell and hopper, a lower bell and hopper, a chamber therebetween, and means for rotating said upper hopper, said upper hopper extending downwardly

into said chamber through an opening in the top of said chamber: sealing means to prevent flow of gases between said chamber and the atmosphere through said opening, said sealing means comprising a flexible cylindrical member positioned in gas-tight relation to said upper hopper and spaced radially therefrom, a cylindrical retaining member against which said flexible cylindrical member slides when said upper hopper is rotated, said retaining member being associated in gas-tight relation with the walls of said chamber and adjacent said opening in the top thereof, and an annular buffer member mounted concentrically, and in fixed relation, with respect to said retaining member, and in sliding relation with respect to said flexible cylindrical member, and adapted to urge said flexible cylindrical member toward said retaining member, said latter two members being positioned substantially concentrically with respect to said upper hopper.

2. In a blast furnace having an upper bell and hopper, a lower bell and hopper, a chamber therebetween, and means for rotating said upper hopper, said upper hopper extending downwardly into said chamber through an opening in the top of said chamber: sealing means to prevent flow of gases between said chamber and the atmosphere through said opening, said sealing means comprising a flexible cylindrical member positioned in gas-tight relation to said upper hopper and spaced radially therefrom, a cylindrical retaining member against which said flexible cylindrical member slides when said upper hopper is rotated, said retaining member being associated in gas-tight relation with the walls of said chamber and adjacent said opening in the top thereof, an annular buffer member mounted concentrically, and in fixed relation, with respect to said retaining member, and in sliding relation with respect to said flexible cylindrical member, and adapted to urge said flexible cylindrical member toward said retaining member, and means for introducing a lubricant between the contacting faces of said flexible cylindrical member and said retaining member, said latter two members being positioned substantially concentrically with respect to said upper hopper.

3. In a blast furnace having an upper bell and hopper, a lower bell and hopper, a chamber therebetween, and means for rotating said upper hopper, the lower end of said upper hopper extending downwardly into said chamber through a circular opening in the top walls of said chamber, thereby defining an annular space between said upper hopper and the edges of said opening: sealing means to prevent flow of gases between said chamber and the atmosphere through said space, said sealing means comprising a flexible cylindrical member attached in gas-tight relation to supporting means, and spaced radially from said upper hopper, said supporting means being attached in gas-tight relation to said upper hopper, a non-yielding cylindrical retaining member against which said flexible cylindrical member slides when said upper hopper is rotated, said retaining member being associated in gas-tight relation with the walls of said chamber and adjacent said opening in the top thereof, and means for introducing a lubricant between the contacting faces of said flexible cylindrical member and said retaining member, said latter two members being positioned substantially concentrically with respect to said upper hopper, said flexible cylindrical member and said retaining member being

so positioned that the major portion of the outer surface of the former member is juxtaposed with the major portion of the inner surface of the latter member, said flexible cylindrical member being adapted to be urged, by the pressure of gas from said chamber against the inner surface of said flexible cylindrical member, against said retaining member so as to effect detailed conformation with the said juxtaposed surface of said retaining member and thereby form a tight seal against escape of said gas between said juxtaposed surfaces.

4. In a blast furnace having an upper bell and hopper, a lower bell and hopper, a walled chamber therebetween, and means for rotating said upper hopper, the lower end of said upper hopper extending downwardly into said chamber through a circular opening in the top walls of said chamber, thereby defining an annular space between said upper hopper and the edges of said opening: sealing means to prevent flow of gases between said chamber and the atmosphere through said space, said sealing means comprising a flexible cylindrical member attached in gas-tight relation to supporting means, and spaced radially from said upper hopper, said supporting means being attached in gas-tight relation to said upper hopper, said flexible cylindrical member and said supporting means being arranged to rotate with said hopper, a non-yielding cylindrical retaining member against which said flexible cylindrical member slides when said upper hopper is rotated, said retaining member being associated in gas-tight relation with the walls of said chamber and adjacent said opening in the top thereof, an annular buffer member mounted concentrically, and in fixed relation, with respect to said retaining member, and in sliding relation with respect to said flexible cylindrical member, and adapted to urge said flexible cylindrical member toward said retaining member, and means for introducing a lubricant between the contacting faces of said flexible cylindrical member and said retaining member, said latter two members being positioned substantially concentrically with respect to said upper hopper.

5. In a blast furnace having an upper bell and hopper, a lower bell and hopper, a chamber therebetween, and means for rotating said upper hopper, said upper hopper extending downwardly into said chamber through an opening in the top of said chamber: sealing means to prevent flow of gases between said chamber and the atmosphere through said opening, said sealing means comprising a flexible cylindrical member supported adjacent its upper edge in gas-tight relation to said upper hopper and spaced radially therefrom, a cylindrical retaining member against which said flexible cylindrical member slides when said upper hopper is rotated, said retaining member being associated in gas-tight relation with the walls of said chamber and adjacent said opening in the top thereof, an annular buffer member mounted concentrically, and in fixed relation, with respect to said retaining member, and in sliding relation with the inner face of said flexible cylindrical member adjacent the lower edge thereof, and adapted to urge said flexible cylindrical member toward said retaining member, and means for introducing a lubricant between the contacting faces of said flexible cylindrical member and said retaining member, said latter two members being positioned substantially concentrically with respect to said upper hopper.

6. In a device having two contiguous bodies with an annular opening between said bodies, one of said bodies being rotatable with respect to the other; sealing means to prevent flow of gases between said bodies through said opening, said sealing means comprising a flexible cylindrical member positioned in gas-tight relation to the inner one of said bodies and spaced radially therefrom, a cylindrical retaining member against which said flexible cylindrical member slides when said inner body is rotated, said retaining member being associated in gas-tight relation with the walls of the outer one of said bodies, an annular buffer member mounted concentrically, and in fixed relation, with respect to said retaining member, and in sliding relation with respect to said flexible cylindrical member, and adapted to urge said flexible member toward said retaining member, and means for introducing a lubricant between the contacting faces of said flexible cylindrical member and said retaining member, said latter two members being positioned substantially concentrically with respect to the axis of said inner body.

7. In a device having two contiguous bodies with an annular opening between said bodies, one of said bodies being rotatable with respect to the other; sealing means to prevent flow of gases between said bodies through said opening from a zone of higher pressure on one side of said opening to a zone of lower pressure on the other side, said sealing means comprising a flexible cylindrical member positioned in gas-tight relation to the inner one of said bodies and spaced radially therefrom, a cylindrical retaining member against which said flexible cylindrical member slides when said inner body is rotated, said retaining member being associated in gas-tight relation with

the walls of the outer one of said bodies, and means for introducing a lubricant between the contacting faces of said flexible cylindrical member and said retaining member, said latter two members being positioned substantially concentrically with respect to the axis of said inner body, said flexible cylindrical member and said retaining member being so positioned that the major portion of the outer surface of the former member is juxtaposed with the major portion of the inner surface of the latter member, said flexible cylindrical member being adapted to be urged, by the pressure of gas from said zone of higher pressure against the inner surface of said flexible cylindrical member, against said retaining member so as to effect detailed conformation with the said juxtaposed surface of said retaining member and thereby form a tight seal against escape of said gas between said juxtaposed surfaces.
